SHIFTING ARRANGEMENT FOR TYPEWRITERS Hans Sippel, Furth, Bay, Germany, assignor to Triumph
Werke Nurnberg A.G., Nurnberg, Germany

Filed Jan. 29, 1958, Ser. No. 719,180

Claims priority, application Germany Jan. 30, 1957

17 Claims. (Cl. 197—74)

The present invention relates to a shifting arrangement for shifting the type lever carrier of a typewriter or similar business machine between two positions in which upper case characters and lower case characters, respectively, are typed by type levers mounted on the carrier.

It is known to support the type lever carrier on two pairs of levers which are pivotally supported on the machine frame. As a rule, the carrier is lowered when it is desired to type upper case letters.

In order to produce uniform imprints of upper case types and of lower case types, the upper case types and the lower case types must be located in exactly the same relative position with respect to the platen when they are operative due to corresponding shifting of the type lever carrier. More particularly, the upper case types and the lower case types must be spaced exactly the same distance from the platen, when they are shifted to operative positions. Also, to achieve perfect imprints, the plane of associated upper case and lower case types, must be parallel to a tangential plane on the portion of the cylindrical platen which cooperates with the types.

In order to obtain the desired conditions, adjustments of the lever means which support the type lever carrier, are necessary. However, the arrangements of the prior art are only capable of a very rough adjustment, for example by means of additional washers, and therefore the constructions of the prior art are incapable of producing imprints of upper case types and lower case types which are of the same strength.

It is one object of the present invention to overcome the disadvantages of the shifting arrangements for type lever carriers according to the prior art, and to provide a shifting arrangement which assures production of exactly equal imprints by upper case types and lower case types.

Another object of the present invention is to provide means for continuously adjusting the position of the turning axis about which the carrier swings during shifting movement, in order to obtain a shifting of the upper case types to the position occupied by the lower case types in the other position of the type lever carrier.

Another object of the present invention is to provide a shifting arrangement which can be continuously adjusted until a condition is obtained in which the upper case type and the lower case type of the same type lever are located in a plane parallel to the tangential plane on a corresponding portion of the cylindrical platen of the typewriter when the respective types are in printing position.

Another object of the present invention is to provide means for continuously adjusting the position of the fulcrum of lever means supporting the carrier until the point at which the carrier is secured to the lever means is in the two shifted positions of the carrier located in a plane which is parallel to a tangential plane on the operative portion of the platen, and parallel to the plane de-

2

fined by the upper case type and lower case type of a type lever in printing position.

With these objects in view, the present invention mainly consists in a shifting arrangement for typewriters, and 5 similar business machines, which comprises, in combination, a support; a type lever carrier; first lever means having one end thereof connected to the carrier for turning movement; second lever means having one end thereof connected to the carrier for turning movement; first 10 supporting means for supporting the other end of the first lever means for turning movement on the support; and second supporting means for supporting the other end of the second lever means for turning movement on the support. According to the present invention, one 15 of the supporting means is continuously adjustable for placing the turning axis of the respective lever means in a selected position relative to the support. This position of the turning axis is so adjusted that the upper case types and the lower case types of type levers in printing 20 position, are located in the same position relative to the platen in the two operative shifted positions of the type lever carrier.

In accordance with the present invention, the axes 25 about which the first and second lever means turn on the support, are spaced from each other the same distance as the points on which the carrier is mounted on the first and second lever means. Preferably, the adjustment is carried out in a plane parallel to a plane passing through the upper case type and the lower case type of a type lever in printing position.

According to one embodiment of the present invention, the second lever means are leaf springs, and the second supporting means include a threaded member which is adjustably threaded into the support.

According to another embodiment of the present invention, the second lever means are mounted on the support by a continuously adjustable pin and slot connection.

According to a further embodiment of the present 40 invention, the second lever means are leaf springs, and are mounted on supporting levers which are continuously adjustable on the support by means of a slot and pin connection.

According to a modification of the present invention, 45 the first lever means include a pair of first levers, and means are provided for adjusting at least one of the first levers until it is exactly parallel to the other of the first levers.

According to another embodiment of the present 50 invention the second lever means include two levers supported on the support by means of a common shaft so that both levers can be simultaneously adjusted.

The novel features which are considered as characteristic for the invention are set forth in particular in the 55 appended claims. The invention itself, however, both as to its construction and its method of operation, together with additional objects and advantages thereof, will be best understood from the following description of specific embodiments when read in connection with the accompanying drawings, in which:

Fig. 1 is a schematic view illustrating the geometrical 60 conditions on which the present invention is based;

Fig. 2 is a fragmentary side view, partly in section, 65 illustrating one embodiment of the present invention, elements of the typewriter which do not form part of the present invention being omitted for the sake of clarity;

Fig. 3 is a fragmentary sectional view of a detail of 70 the embodiment shown in Fig. 2;

Fig. 4 is a fragmentary side view illustrating a detail 75 of another embodiment of the present invention;

Fig. 5 is a fragmentary side view illustrating a detail of a further embodiment of the present invention;

Fig. 6 is a fragmentary side view illustrating another embodiment of the present invention; and

Fig. 7 is a fragmentary plan view illustrating a detail of the construction shown in Fig. 2.

Referring now to the drawings, and more particularly to Figs. 1 and 2, the operational principle will be explained. On a support 1, which is part of the machine frame, first lever means 2 are mounted which include a pair of first levers 2 turnably mounted on a shaft 3. The free ends of levers 2 are turnably connected by pins 5 to a type lever carrier 4. At least one of the levers 2 has a hole 2a to which a linkage, not shown, is attached for connecting the lever means 2 with the shift key of the typewriter. Second lever means 6 include a pair of second levers which are secured to the carrier 4 at two points 8 which are superimposed in the side views of Figs. 1 and 2. The other ends of the second levers 6 are adjustably secured to the support 1. The adjustable means by which the second lever means 6 are mounted on the support 1, and the various constructions of the second lever means 6, will be described hereinafter in greater detail. A set of type levers 14 are mounted on the carrier 4 for turning movement about shaft means 13. The type levers 14 are connected by suitable linkage means, not shown, to the keyboard of the typewriter. Fig. 2 shows a type lever in printing position in which its stop portion 15 abuts on the stop 16 of the segment-shaped part 12 of the carrier 4. The type head 17 carries a lower case type 18, and an upper case type 19. The printing faces of the types 18 and 19 on the same type lever are located in a plane 50 when the stop portions 15 and 16 engage each other, and this plane is parallel to a tangential plane 51 on the operative portion of the platen 20. The distance between the planes 50 and 51 is D. This relative position between the types 18 and 19 and the platen 20 is obtained by the shifting arrangement of the present invention which will now be described mainly with reference to Fig. 1.

In Fig. 1, the reference numeral 5 designates a first axis, the reference numeral 3 designates a second axis, the reference numeral 8 designates a third axis, and the reference numeral 7 designates a fourth axis. In order to obtain the same distance D between the upper case types and the lower case types and the platen 20, it is necessary that the distance A between the second axis 3 and the fourth axis 7 is equal to the distance B between the first axis 5 and the third axis 8. The two positions 6 and 6' of the second lever means are spaced equal angles β from a plane perpendicular to the plane passing through the two positions 8 and 8' of the third axis when the distances A and B are equal. The plane passing through the two positions 8 and 8' of the third axis is parallel to the plane 50. In the event that the axis 7 is placed too high, that is if the distance A is greater than the distance B, the carrier 4 would not be parallel to the plane 50 in shifted position, but would assume an inclined position so that the upper case types would be spaced a greater distance than the lower case type, resulting in a weaker impact. If the conditions are reversed, and the axis 7 is placed too low, the type lever carrier 4 assumes an oppositely inclined position, when shifted, so that the distance between lower case types and platen becomes too small resulting in a stronger impact.

In both cases, it is necessary to adjust the axis 7 until the distances A and B are exactly equal. The stepwise adjustment is insufficient, and in accordance with the present invention the adjustment of the position of the axis 7 is continuously carried out until the desired position is exactly obtained. According to one embodiment of the present invention illustrated in Fig. 2, the second lever means 6 are a pair of leaf springs located behind each other in the side view of Fig. 2. The ends of the leaf spring levers 6 are secured to the carrier 4 and to the

support 1, respectively. Screws 40 are threaded into the carrier 4 and pass through bores in the leaf springs 6. The other ends of leaf springs 6 are secured to the support 1 by adjustable supporting means. As shown in Figs. 2 and 3, the leaf springs 6 are secured to a threaded sleeve 9 by means of a screw 10. The threaded sleeve 9 engages a threaded bore in the support 1 and has a head 9a cooperating with the head of screw 10. When the nut 11 is loosened, the threaded sleeve 9 can be adjusted, and tightened again by nut 11. The axis of the threaded sleeve 9 extends parallel to the plane 50. The leaf spring levers 6 move between the position shown in solid lines, and the position shown in broken lines in Fig. 2 when the carrier 4 is shifted. During such movement, the springs 6 are bent about the axes 7 and 8 which are defined by the bending lines of the leaf spring levers 6. As explained with reference to Fig. 1, it is necessary to exactly adjust the position of the axis 7 defined by the bending lines of the leaf springs 6 which are superimposed in the side view of Fig. 2. As best seen in Fig. 3, the supporting means are adjusted by first loosening the nut 11, whereupon the threaded sleeve 9 is screwed into or out of the support 1. When the desired position is reached, the nut 11 is again tightened whereby the position of the axis 7 is defined. The two supporting means 9, 10, 11 of the two levers 6 are adjusted to exactly the same height so that a single axis 7 is formed by the bending lines of the levers 6.

The embodiment shown in Fig. 4 constitutes a modification of the adjustable supporting means by which the turning axis of the upper levers is adjusted. In the embodiment of Fig. 4, the two levers 6a are rigid and mounted on two angular levers 23. Lever 23 has an elongated slot 22 which extends in direction of the plane 50. The angular lever 23 has two other elongated slots 24 and is adjustably secured by screws 24a to the support 1. The levers 6a are, respectively, mounted on a threaded pin 21 for turning movement about the axis 7, and the threaded means 21 pass through the elongated slot 22 and are secured by a suitable nut means to the supporting means 23. When the threaded means 21 are loosened, the position of the turning axis 7 of the levers 6a can be adjusted. It will be noted that the slot 22 permits a continuous adjustment until the axis 7 is located at exactly the desired place. The slots 24 permit an additional adjustment in the direction of the arrow E. The other ends of the levers 6a are secured by pivot means 55 to the carrier 4 so that a relative turning movement between the levers 6a and the carrier 4 about the axis 8 is possible.

In the embodiment of Fig. 5, the upper lever means are again two leaf springs 6. The general arrangement of the embodiment of Fig. 5 corresponds to the showing of Fig. 2, but the adjustable supporting means by which a variation of the position of the axis 7 is obtained, are modified. A shaft 27 is mounted on the support 1 and carries two angular levers 26. Each angular lever 26 has a flange on which one end of a leaf spring lever 6 is mounted by means of a screw 25. The other arm of each lever 26 has an elongated slot 28 through which a screw 29 passes. When the screws 29 are loosened, the levers 26 can be turned together to adjust the position of the bending lines 7 of the two leaf spring levers 6 whereby the position of the axis 7 can be continuously adjusted until the desired position is obtained. The embodiment of Fig. 6 is similar to the embodiment of Fig. 5, but employs rigid levers 6a instead of leaf springs. Similar to the arrangement shown in Fig. 4, the levers 6a are turnable on threaded pins 30 which pass through elongated slots in angular levers 31. The two angular levers 31 are supported on a shaft 32 and turn together for adjustment of the position of the axis 7. A slot 33 in the other arm of lever 31 permits the turning of the levers 31 when the screws 33 are loosened. Screws 33 pass

into threaded bores of the support 1. The other ends of the lever 6a are pivotally secured to the carrier 4, as shown in Fig. 4.

Figs. 2-6 illustrate modifications of the continuously adjustable supporting means for the upper lever means. The lower lever means 2 also include two levers which are turnably connected to the carrier by pivot pins 5. It is necessary that the two levers 2, which are superimposed in Fig. 2, are exactly parallel to each other so that the axis 5 of Fig. 1 is parallel to the axes 7 and 8 of Fig. 1. Consequently it is preferred, to make the pivotal connection of one of the two levers 2 adjustable, and an arrangement for achieving this purpose is illustrated in Fig. 7. It will be understood that the construction of Fig. 7 can be combined with any of the above-described embodiments of the present invention, and advantageously cooperates with each embodiment. As shown in Fig. 7 one lever 2 is turnably mounted on the shaft 3, and has at the other end thereof a bushing 34. The pin 35 of an eccentric member 36 passes through the bushing 34, and carries a ring 37 which prevents axial movement of the eccentric member 36. The eccentric member 36 passes into a corresponding bore in the carrier 4. A set screw 38 fixes the eccentric member 36 in adjusted position to the carrier 4, whereby the position of the axis 5 in Fig. 1 is determined by the axis of the pin 35. The arrangement illustrated in Fig. 7 permits the adjustment of one of the levers 2 until the two levers 2 are exactly parallel.

It will be understood that each of the elements described above, or two or more together, may also find a useful application in other types of shifting arrangements for typewriters and business machines differing from the types described above.

While the invention has been illustrated and described as embodied in a shifting arrangement for the type lever carrier of a typewriter including a continuously adjustable element, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Shifting arrangement for typewriters comprising, in combination, a support; a type lever carrier; first lever means having one end thereof connected to said carrier for turning movement; second lever means having one end thereof connected to said carrier for turning movement; first supporting means for supporting the other end of said first lever means for turning movement on said support; and second supporting means for supporting the other end of said second lever means for turning movement on said support, one of said supporting means including continuously adjustable threaded means in threaded connection with said support for placing the turning axis of the respective lever means in a selected position relative to said support whereby said carrier is supported by said lever means on said support for movement between two positions in which the upper case types and the lower case types of type levers supported on said carrier are adapted to be respectively located in the same position relative to a platen when in printing position.

2. Shifting arrangement for typewriters comprising, in combination, a support; a type lever carrier; first lever means having one end thereof connected to said carrier

for turning movement; second leaf spring lever means located above said first lever means and having one end thereof connected to said carrier for turning movement; first supporting means for supporting the other end of said first lever means for turning movement on said support; and second supporting means for supporting the other end of said second lever means for turning movement on said support, said second supporting means including continuously adjustable threaded means in threaded connection with said support for placing the turning axis of said second leaf spring lever means in a selected position relative to said support whereby said carrier is supported by said lever means on said support for movement between two positions in which the upper case types and the lower case types of type levers supported on said carrier are adapted to be respectively located in the same position relative to a platen when in printing position.

3. Shifting arrangement for typewriters comprising, in combination, a support; a type lever carrier; first lever means having one end thereof connected to said carrier for turning movement; second lever means located above said first lever means and having one end thereof connected to said carrier for turning movement; first supporting means for supporting the other end of said first lever means for turning movement on said support; and second supporting means for supporting the other end of said second lever means for turning movement on said support, said second supporting means including a lever pivotally mounted on said support and having an arm supporting said other end of said second lever means for movement about a turning axis and another arm formed with an elongated slot, and attaching means passing through said slot and attached to said support for securing said lever to said support in continuously adjusted positions for placing said turning axis of said second lever means in a selected position relative to said support whereby said carrier is supported by said lever means on said support for movement between two positions in which the upper case types and the lower case types of type levers supported on said carrier are adapted to be respectively located in the same position relative to a platen when in printing position.

4. A shifting arrangement as set forth in claim 3 wherein said attaching means include a threaded bolt passing through said slot and threadedly engaging said support.

5. Shifting arrangement for typewriters comprising, in combination, a support; a type lever carrier; first leaf spring lever means having one end thereof connected to said carrier for turning movement; first supporting means for supporting the other end of said first leaf spring lever means for turning movement on said support; second leaf spring lever means including a pair of second leaf spring levers each second leaf spring lever having one end thereof connected to said carrier for turning movement; and second supporting means for supporting the other ends of said second leaf spring levers on said support, said second supporting means including a shaft mounted on said support, a pair of levers secured to said shaft and having first arms respectively supporting the other ends of said second leaf spring levers for pivotal movement about a common turning axis, each lever having a second arm formed with an elongated slot, and attaching means respectively passing through said slots and attached to said support for securing said levers to said support in continuously adjusted positions for placing said common turning axis of said second leaf spring levers in a selected position relative to said support whereby said carrier is supported by said leaf spring lever means on said support for movement between two positions in which the upper case types and the lower case types of type levers supported on said carrier are adapted to be respectively located in the same position relative to a platen when in printing position.

6. Shifting arrangement for typewriters comprising, in

combination, a support; a type lever carrier; first leaf spring lever means having one end thereof connected to said carrier for turning movement; first supporting means for supporting the other end of said first leaf spring lever means for turning movement on said support; second leaf spring lever means including a pair of second leaf spring levers each second leaf spring lever having one end thereof connected to said carrier for turning movement; and second supporting means for supporting the other ends of said second leaf spring levers on said support for turning movement about a common turning axis, said second supporting means being adjustable for placing said common turning axis of said second leaf spring levers in a selected position relative to said support whereby said carrier is supported by said leaf spring lever means on said support for movement between two positions in which the upper case types and the lower case types of type levers supported on said carrier are adapted to be respectively located in the same position relative to a platen when in printing position.

7. Shifting arrangement for typewriters, comprising, in combination, a support; a type lever carrier; first lever means including a pair of first levers; a shaft mounted on said support and turnably supporting said first levers; two pivot members supporting said carrier on said first levers for turning movement, one of said pivot members being adjustable relative to said carrier for placing said first levers in a parallel position; second lever means having one end thereof connected to said carrier for turning movement; and supporting means for supporting the other end of said second lever means for turning movement on said support said supporting means being spaced from said shaft and being continuously adjustable for placing the turning axis of said second lever means in a selected position relative to said support in which the axis of said shaft and said turning axis of said second lever means are exactly spaced said distance from each other whereby said carrier is supported by said lever means on said support for movement between two positions in which the upper case types and the lower case types of type levers supported on said carrier are adapted to be respectively located in the same position relative to a platen when in printing position.

8. Shifting arrangement for typewriters, comprising, in combination, a support; a type lever carrier; first lever means including a pair of first levers; a shaft mounted on said support and turnably supporting said first levers; two pivot members supporting said carrier on said first levers for turning movement, one of said pivot members being adjustable relative to said carrier for placing said first levers in a parallel position and including a turnable eccentric member turnably mounted in said carrier; second lever means having one end thereof connected to said carrier for turning movement; and supporting means for supporting the other end of said second lever means for turning movement on said support, said supporting means being spaced from said shaft and being continuously adjustable for placing the turning axis of said second lever means in a selected position relative to said support in which the axis of said shaft and said turning axis of said second lever means are exactly spaced said distance from each other whereby said carrier is supported by said lever means on said support for movement between two positions in which the upper case types and the lower case types of type levers supported on said carrier are adapted to be respectively located in the same position relative to a platen when in printing position.

9. A shifting arrangement as set forth in claim 8 wherein said first levers are located below said second levers.

10. Shifting arrangement for typewriters comprising, in combination, a support; a type lever carrier; a set of type levers including type heads having upper case types and lower case types spaced from each other in one direction, each type lever being mounted on said carrier

for movement to a printing position in which said types thereof are located in a first plane; lever means having one end pivotally connected to said carrier; and adjustable means turnably supporting the other end of said lever means on said support for turning movement about a turning axis so that said carrier and said type levers are movable along part-circular paths about said turning axis between two positions, respectively, in which said upper case types and said lower case types, respectively, are adapted to cooperate with a platen when the respective type lever is in printing position, said adjustable means being continuously adjustable parallel to said direction and said first plane for placing said turning axis in a second plane perpendicular to said first plane and equally spaced in said direction from the locations of said other ends of said lever means in said two positions of said carrier.

11. Shifting arrangement for typewriters, comprising, in combination, a support; a type lever carrier; first lever means having one end thereof connected to said carrier for turning movement about a first axis and having the other end thereof mounted on said support for turning movement about a second axis; second lever means located above said first lever means and having one end thereof connected to said carrier for turning movement about a third axis, said first and third axes being spaced from each other a first distance in one direction; and supporting means for supporting the other end of said second lever means on said support for turning movement about a fourth axis, said supporting means having a part spaced from said support and being continuously adjustable in said one direction for placing said fourth axis in a position in which it is exactly spaced in said direction said distance from said second axis so that said carrier is supported on said first and second lever means for movement between two positions in which the upper case types and the lower case types of type levers supported on said carrier are adapted to be respectively located in the same position relative to a platen when in printing position.

12. Shifting arrangement for typewriters comprising, in combination, a support; a type lever carrier; a set of type levers including type heads having upper case types and lower case types spaced from each other in one direction, each type lever being mounted on said carrier for movement to a printing position in which said types are located in a first plane; first lever means having one end thereof connected to said carrier for turning movement about a first axis and having the other end thereof mounted on said support for turning movement about a second axis; second lever means located above said first lever means and having one end thereof connected to said carrier for turning movement about a third axis, said first and third axes being spaced from each other a first distance in said one direction; and supporting means for supporting the other end of said second lever means on said support for turning movement about a fourth axis, said supporting means having a part spaced from said support and being continuously adjustable in said one direction for placing said fourth axis in a position in which it is exactly spaced in said direction said distance from said second axis so that said carrier is supported on said first and second lever means for movement between two positions in which the upper case types and the lower case types of type levers supported on said carrier are respectively located in the same position relative to a platen when in printing position.

13. Shifting arrangement for typewriters comprising, in combination, a support; a type lever carrier; a set of type levers including type heads having upper case types and lower case types spaced from each other in one direction, each type lever being mounted on said carrier for movement to a printing position in which said types are located in a first plane; first lever means having one end thereof connected to said carrier for turning movement about a first axis and having the other end thereof

mounted on said support for turning movement about a second axis; second lever means located above said first lever means and having one end thereof connected to said carrier for turning movement about a third axis, said first and third axes being spaced from each other a first distance in said one direction; and supporting means for supporting the other end of said second lever means on said support for turning movement about a fourth axis, said supporting means being continuously adjustable in said one direction and parallel to said first plane, said supporting means being positioned relative to said carrier for placing said fourth axis in a second plane perpendicular to said first plane and equally spaced in said direction from the locations of said third axis in said two positions of said carrier so that said carrier is supported on said first and second lever means for movement between two positions in which the upper case types and lower case types of said type levers supported on said carrier are respectively located in the same position relative to a platen when in printing position.

14. Shifting arrangement for typewriters comprising, in combination, a support; a type lever carrier; a set of type levers including type heads having upper case types and lower case types spaced from each other in one direction, each type lever being mounted on said carrier for movement to a printing position in which said types are located in a first plane; first lever means having one end thereof connected to said carrier for turning movement about a first axis and having the other end thereof mounted on said support for turning movement about a second axis; second lever means located above said first lever means and having one end thereof connected to said carrier for turning movement about a third axis, said first and third axes being spaced from each other a first distance in said one direction; and supporting means 35 for supporting the other end of said second lever means on said support for turning movement about a fourth axis, said supporting means having a part spaced from said support and being continuously adjustable in said

one direction and parallel to said first plane, said supporting means being positioned relative to said carrier for placing said fourth axis in a second plane perpendicular to said first plane and equally spaced in said direction from the locations of said third axis in said two positions of said carrier and in a position in which said fourth axis is exactly spaced in said direction said distance from said second axis so that said carrier is supported on said first and second lever means for movement between two 10 positions in which the upper case types and the lower case types of said type levers supported on said carrier are respectively located in the same position relative to a platen when in printing position.

15. A shifting arrangement as set forth in claim 14 wherein said second lever means include a pair of leaf springs respectively connected at the ends thereof to said carrier and to said supporting means.

16. A shifting arrangement as set forth in claim 15 wherein said supporting means include threaded means 20 threaded into said support and having an axis extending in said one direction for continuously adjusting the position of said fourth axis.

17. A shifting arrangement as set forth in claim 14 wherein said second lever means include a pair of levers 25 turnably connected at one pair of ends thereof to said carrier; and wherein said supporting means include a member having a slot extending in said one direction; and threaded means passing through said slot and turnably supporting said second levers on said member whereby the position of said fourth axis can be adjusted by continuously moving said threaded means in said slot.
